UNITED STATES PATENT OFFICE

CARLOS WITTENMYER, OF MOUNT CLEMENS, MICHIGAN

VISIBLE INDEX FILING DEVICE

Application filed November 23, 1927. Serial No. 235,181.

The present invention relates to "visible index" filing devices for cards or other records.

Among the objects of the invention is to enlarge the field of use of such devices by making them capable of functions not heretofore possible.

Another object is a device of the type mentioned which can be used for filing loose memora and in which such loose memoranda can be easily located.

Another object is such a device having provision for a visible index whether the card title is at the top or bottom or both.

Another object is a device of the type mentioned in which the records are vertical, visibly indexed, but may be placed substantially horizontal for the purpose of entry without removal from the holder.

Other objects will readily occur to those skilled in the art upon reference to the following description and accompanying drawings in which:—

Fig. 1 is a partial perspective view showing one section of the file in fully opened position;

Fig. 2 is a perspective view showing such a file partly closed and showing parts in section;

Fig. 3 is a vertical section through the drawer;

Fig. 4 is an elevation of one form of holder;

Fig. 5 is a view similar to Fig. 1 but showing a different part in section;

Fig. 6 is an end view of the drawer housing;

Fig. 7 shows the connecting link;

Fig. 8 shows the stop member;

Fig. 9 shows bolts for the stop member;

Fig. 10 shows a bottom plate for the stop member;

Fig. 11 is an end of the drawer;

Fig. 12 shows the drawer when in closed position in its housing partly broken away to show rear portions of the drawer; and

Fig. 13 is a view of a slight modification of the universal drawer stop.

As shown in the drawings, the device consists of a housing or drawer holder 20 and a bottomless drawer or slide 21, the former be-

ing provided with means to prevent removal of the drawer when the device is assembled. This means is shown in Fig. 6 as consisting of tongues 22 formed as continuations of sides and adapted to be turned in at right-angles 55 as shown in Figs. 1 and 2.

The drawer 21 comprises two main portions, a stop member and a main portion, connected by a swivel joint so that the main portion may be pulled clear of the housing and turned over when desired.

The stop member consists of the parts shown in Figs. 8, 9 and 10. The first of these is the rectangular retaining follower 25 of such size as to fit in and slide easily in housing 20, and provided with a hole 26 in its front face and holes 27 in its bottom. This retaining follower 25 is secured to a bottom plate 28 slotted as shown at 29 for the reception of bolts 30 passing through holes 27 into the same. The bolts are provided with shoulders fitting loosely in slots 29 and nuts 31 adapted to screw against the shoulders so as to permit retaining follower 25 to move forward or backward on plate 28 thereby permitting the front face of the retaining follower to move out to a position flush with the outer edge of the housing where it is retained by the ends of the plate 28 engaging the inside surfaces of the tongues 22 at the front 70 corners of the housing.

The main drawer portion 21 consists of a rectangular frame whose front and rear members 35 and 36 are flanged inwardly at the bottom as at 37. The sides of the drawer 21 are channel-shaped in cross-section, the outer wall 40 of the channel being wider than the inner side 41, thereof, so that the latter's upper edge is lower than the lower edge of the former, the channel opening being on the upper side. The rear member 36 is provided with a long horizontal slot 42 adapted to contact with one end of the bolt 43 forming the connecting link with the stop above described. This bolt 43 has its head 44 in the form of a ball slightly larger than hole 26 in member 25 and at its other end is provided with a reduced portion 45 fitting loosely in slot 42, the end having a nut 46. When the bolt 43 is inserted in member 25 from the rear and 95

secured in slot 42 by nut 46, the drawer is permitted a lateral movement, may be rotated and inverted on its longitudinal axis, and may be swung at an angle for purposes to be mentioned later.

Hinged in the channels 40 are two L-shaped locking plates 50, having their flanges turned inwardly and located a little below the upper edge of wall 41. These plates 50 are provided 10 at their forward ends with ears 51 through which they are connected by means of links 52 to a centrally located lever 53, one plate being connected to the top and one to the bottom of the lever, which latter is provided with 15 a spring 54 connected to front member 35 and arranged to hold the plates in their inner position. Lever 53 may be provided with any suitable manipulating means such as the rod 55 attached thereto and projecting thru the 20 front of the drawer, the rod bearing on its forward or face end, a knob 56 to be grasped by the operator.

The form of drawer just described is designed to be used with a card holder or pocket 25 such as shown in Figs. 3 and 4.

In Fig. 3 a flat pocket of suitable material is shown at 60, supported on a wire or rod 61 which is bent near its ends to form U-shaped portions 62 with the extremities 63 of the 30 wire brought back to alignment or substantially so. Also mounted on rod 61 between the portions 62 is a pair of spacers 64 consisting preferably of small cylindrical pieces of wood. In this form of record holder, 35 records may be entered on the outside and/or detached memoranda may be placed in the pocket, and in order to facilitate finding the latter, the pocket is notched as at 65 so that such memoranda may be seen or discovered 40 by running the finger along the series of notches where the pockets are hanging in the position shown in Fig. 2, the pockets being open at the top. If desired this end of the pocket may be left open (not shown) so that 45 the records when found may be withdrawn therefrom using the same hand.

Fig. 4 shows a similar record holder intended for cards. In this form, a frame 70 is supported by a rod 61 and other parts as in 50 Fig. 3. The frame 70 is of U-section to embrace the edges of a card 71 and is either cut away on one side at the bottom as at 72 or made of transparent material to render visible the lower edge as indicated.

55 These record holders are of proper width to drop down between the channels 40 with the U-portions 62 of the rods resting upon the walls 41. In this position, the flanges of plates 50 will overlie the extremities 63 of the rods 61 and hold the record holders in 60 place.

As it is intended that the record holders shall lie substantially flat when the drawer is within the housing 20, it is obvious that 65 the foremost holder 60 must be no closer to

the front 35 of the drawer 21 than a distance equal to the vertical dimension of the holder 60. In order to insure this relation, a stop member 80 is provided on one or both channel members 40 it being pivoted at 81 to allow its rear end to drop under rod 61 when the front or handle end thereof is elevated as shown in dotted lines to allow moving the holders forward to permit insertion or removal of a holder or insertion or removal of matter from a pocket.

70 Fig. 13 shows a modified form of swiveled connecting link. In this form, the stop member is of the same construction as that already described except that the hole 26a is key-hole-shaped to permit ready insertion of the ball head of link 43a and the latter is provided at its other end with a small pulley 46a adapted to roll on a track or guide in the form of a wire stirrup or loop 42a secured 75 across the rear member 36a of the drawer 21. These parts have the same functions as those described above and are intended to permit 80 the rotation or inversion and swinging of the drawer as well as allow a sidewise movement.

85 In the operation of the device, one or more of the record holders is placed in position in the drawer as shown in Fig. 2 with the drawer partially or completely withdrawn from the housing. When the drawer is pushed into the 90 housing, the holder will be swung to approximately horizontal position as their lower portions strike the bottom housing 20. Withdrawal of the drawer permits the holders to swing into the position shown in Fig. 2. In 95 the latter position, the upper margins of the 100 holders are all visible to the operator. Reversal or inversion of the drawer to inverted position by rotating as aforementioned permits the holders to lie substantially flat on 105 each other and thereby render the lower margins of the holders visible. This reversibility of the drawer allows ready access to either 110 side of the card as well as allowing indexing of the latter on both sides thereof.

115 It will thus be seen that either of the horizontal edges of the record holders is easily visible and that, while the latter are normally vertical when the drawer is out, they may be placed horizontally for the purpose of new 120 entries or other consultation.

125 It will be noted from Figures 1, 5 and 13 that when the drawer is pulled out of the housing to permit its reversal, it will drop down to almost vertical position. In such 130 position, the entry or change of the records may be found inconvenient due to the position of the drawer. In order to permit use of the records comfortably and conveniently without withdrawal and dropping of the 135 drawer to this position and in order to prevent its dropping to this position inadvertently, a suitable catch or intermediate stop (not shown) may be provided if desired to prevent the rear end of the rectangular frame 21 leav-

ing the housing unless the intermediate stop or catch is voluntarily foiled.

Now having described the invention and the preferred forms of embodiment thereof, it is to be understood that the said invention is to be limited not to the specific details herein set forth but only by the scope of the claims which follow.

I claim:—

10 1. A filing device comprising a housing, a bottomless drawer adapted to slide in and out of said housing, record holders carried by said drawer and adapted to be suspended from the side members thereof, and means supporting the drawer in a manner permitting the inversion thereof without its being completely detached from the housing.

2. A filing device comprising a housing, a bottomless drawer adapted to slide in and out of said housing, transparent record holders carried by said drawer and adapted to be suspended from the side members thereof, and means supporting the drawer in a manner permitting the inversion thereof without 25 its being completely detached from the housing.

3. A filing device comprising a housing, a bottomless drawer adapted to slide in and out of said housing, record holders carried by said drawer and adapted to be suspended from the sides thereof, securing means for said holders, means whereby said securing means may be released and means to return the last-mentioned means automatically to 25 holder securing position.

4. A filing device comprising a housing, a bottomless drawer adapted to slide in and out of said housing, a stop member for preventing complete removal of the drawer from the housing, record holders carried by said drawer and adapted to be suspended from the side members thereof, and means supporting the drawer in a manner permitting the inversion thereof without its being completely detached from the housing.

5. A filing device comprising a housing, a bottomless drawer adapted to slide in and out of said housing, a stop member for normally preventing complete removal of the drawer from the housing, but from which said drawer may easily be detached, record holders carried by said drawer and adapted to be suspended from the side members thereof, and means supporting the drawer in a manner permitting the inversion thereof without its being completely detached from the housing.

6. A filing device comprising a housing, a bottomless drawer adapted to slide in and out of said housing, a stop member for preventing complete removal of the drawer from the housing, record holders carried by said drawer and adapted to be suspended from the side members thereof, and means supporting the drawer in a manner permitting the inversion thereof without its being com-

pletely detached from the housing, said means comprising a swiveled connection between the main portion of the drawer and the stop member.

7. A filing device comprising a drawer housing and a bottomless drawer therefor, and record holders of greater depth than the depth of said drawer suspended from the side members thereof by means permitting swinging of said holders up into the plane of said drawer.

8. A filing device comprising a drawer housing and a bottomless drawer therefor, record holders of greater depth than the depth of said drawer suspended from the side members thereof by means permitting swinging of said holders up into the plane of said drawer and spacers on said holders, whereby when the latter are swung up a considerable portion of the upper margin of each holder is visible.

9. A filing device comprising a housing, a bottomless drawer slidable therein, and means supporting the drawer in a manner permitting the inversion thereof without its being completely detached from the housing, record holders of greater depth than the depth of said drawer suspended from the side members thereof by means permitting swinging of said holders up into the plane of said drawer, and spacers for said holders whereby a considerable portion of the uppermost margin of each holder is visible in either position of the drawer.

10. In a filing device, a bottomless drawer comprising a rectangular frame having channeled side members, record holders adapted to rest on the inner walls of said channels and means within said channels adapted to coact with the ends of said holders to retain them upon said frame.

11. In a filing device, a bottomless drawer comprising a rectangular frame, record holders suspended between the side members of said frame and movable lengthwise thereof and means to lock said holders against movement into a portion of the frame.

12. In a filing device, a bottomless drawer, means supporting said drawer in a manner such that the drawer may be inverted on said means, record holders suspended from the side members of said drawer, and means adapted to secure said holders against falling out when said drawer is inverted.

13. In a filing device, a record holder comprising a pocket having a notch in one vertical edge whereby the contents are exposed and having an edge open to facilitate withdrawal of records.

14. A filing device comprising a housing, a drawer adapted to slide in and out of said housing, record holders carried by the sides thereof, securing means for said holders, means whereby said securing means may be released and means to return the last-men-

tioned means automatically to securing position.

15. In a filing device, a drawer comprising
channeled side members, record holders
adapted to rest on the inner walls of said
channels and means within said channels
adapted to coact with the ends of said hold-
ers to retain them upon said walls.
